UNITED STATES PATENT OFFICE.

AUGUSTUS G. PARKHURST, OF MINNEAPOLIS, MINNESOTA.

DESIGN FOR A TILE.

SPECIFICATION forming part of Design No. 16,777, dated July 6, 1886.

Application filed May 10, 1886. Serial No. 201,752. Term of patent 7 years.

To all whom it may concern:

Be it known that I, AUGUSTUS G. PARKHURST, a citizen of the United States, residing at Minneapolis, in the county of Hennepin and State of Minnesota, have invented and produced a new and original Design for Pavement-Tiles, of which the following is a specification, reference being had to the accompanying drawings, forming part thereof.

Figure 1 is a plan of one of my newly-designed tiles. Fig. 2 is a plan of a section of pavement formed of these tiles.

The main feature of my design consists in a tile in substantially the form of an irregular Greek cross. The outline of the tile is made up of the opposite parallel lines 1 1 and 2 2, the opposite parallel lines 1 4 1 4 and 2 3 2 3 at right angles to the lines 1 1 and 2 2, the opposite parallel lines 5 5 at right angles to the lines 1 1 and 2 2 and parallel with the

lines 1 4 and 2 3. The distance between the points 3 4 is greater than the length of the lines 5 5, so that the lines 5 4 and 5 3 are oblique, as shown, thereby giving a pleasing variety to the outline of the tile. 25

The tiles, or part of them, may be given any desired color.

I claim as my invention—

The design for a pavement-tile herein shown and described, the same consisting of a tile 30 whose boundary-walls comprise a figure of the shape of an irregular Greek cross, as set forth.

In testimony whereof I have hereunto set my hand this 5th day of April, 1886.

AUGUSTUS G. PARKHURST.

In presence of—

A. C. PAUL,
RICHARD PAUL.
